UNITED STATES PATENT OFFICE.

GEBHARD WAGER, OF UNION CITY, PENNSYLVANIA.

WINE AND CIDER PRESS.

SPECIFICATION forming part of Letters Patent No. 312,235, dated February 10, 1885.

Application filed December 13, 1884. (No model.)

To all whom it may concern:

Be it known that I, GEBHARD WAGER, of Union City, in the county of Erie and State of Pennsylvania, have invented certain new and useful Improvements in Wine and Cider Presses; and I do hereby declare the following to be a full, clear, and exact description of the invention, such as will enable others skilled in the art to which it pertains to make and use it, reference being had to the accompanying drawings, which form part of this specification.

My invention relates to an improvement in cider-presses; and it consists in a separator for dividing the cheeses, and which is provided with a solid bottom and openings through its sides, so that the cider from each separate cheese can be run into a separate barrel, as will be more fully described hereinafter.

The object of my invention is to provide a separator for cider and wine presses whereby the fruit of a number of persons can be pressed at the same time and thus effect a great saving in time.

Figure 1 is a perspective of a press embodying my invention. Fig. 2 is a perspective of one of the separators.

A represents the platform of an ordinary cider-press, and upon which are placed a number of separators, which are piled one upon the other in the usual manner with the cheeses between them. Each separator consists of a rectangular frame of suitable size and depth, and each one has a solid bottom, so that there can be no leakage through it. Through opposite side walls of each separator is made an opening, B, so that a rubber tube or pipe of any kind can be connected to the tray or separator for the purpose of running the cider into a barrel or other receptacle to receive it. Holes are made in opposite sides so that if the separator should tip to one side, as is

frequently the case, the cider will run readily out on one side or the other. The cider which runs out on the platform runs into a barrel, C, placed to receive it, while the cider from the separator placed above the lowest cheese runs into a barrel, D, and that from the next separator above runs into another barrel, F, and so on. By this construction of the separators the fruit of a number of different persons can be pressed at the same time without any danger of getting the cider mixed. This construction also enables a great saving in time to be made, for there is no necessity of having to press the fruit of each one separately.

I do not limit myself to any precise construction, for this may be varied without departing from the spirit of my invention. Metallic plates having tubes attached to them may be used and applied to each hole that is made through the sides of the separators, and thus adapted to have the rubber tubes applied directly to them.

I am aware that in oil-presses each separator is provided with an opening or discharge, but in no case have they been made with solid bottom and side walls and tubes used to convey away the cider to separate casks, as here shown.

Having thus described my invention, I claim—

The combination of a series of separators, each one having a solid bottom and side walls, and openings through the walls, with the tubes which conduct away the cider to the barrels, substantially as shown.

In testimony whereof I affix my signature in presence of two witnesses.

GEBHARD WAGER.
